CLAIM

The ornamental design for a display box, as shown and described.

DESCRIPTION

1. Display box

1.1 shows a right perspective view of the first embodiment of a display box;

1.2 shows a front view of 1.1;

1.3 shows a left perspective view of the second embodiment of a display box;

1.4 shows a front view of 1.3;

1.5 shows a top right view of 1.3; and

1.6 shows a top left view of 1.3.

The intended use of the display box is for hologram-like images. The display box has a transparent front panel. The broken lines portions of the article form no part of the claimed design.
